UNITED STATES PATENT OFFICE.

PATRICK A. NIRDLINGER, OF CHICAGO, ILLINOIS.

REFLECTOR.

1,363,261.

Specification of Letters Patent. Patented Dec. 28, 1920.

Application filed February 24, 1919. Serial No. 278,664.

To all whom it may concern:

Be it known that I, PATRICK A. NIRDLINGER, a citizen of the United States, residing at Chicago, in the county of Cook and 5 State of Illinois, have invented certain new and useful Improvements in Reflectors, of which the following is a specification.

This invention has for its object the provision of a reflector and light which shall be 10 of improved construction and operation.

The invention is exemplified in the combination and arrangement of arts shown in the accompanying drawings and described in the following specification, and it is more 15 particularly pointed out in the appended claims.

In the drawings—

Figure 1 is a section through a projector or flood light provided with a reflector embodying the present invention. 20

Fig. 2 is a plan view of the lamp mounting shown in Fig. 1.

In the construction of reflectors for flood lights and similar purposes, as well as in 25 the manufacture of plain reflectors it has been the common practice to coat the back of a piece of glass with a metallic substance, such as mercury, and use the surface of the metallic coating adjacent the glass as the reflecting surface. It has also been common 30 to use polished metal surfaces for reflecting purposes. Where a glass reflector is used in conjunction with a source of light, the heat from the light source will cause the metallic 35 coating to peel after a period of use, and the construction of accurately-shaped concave mirrors of glass is also expensive. The fact that the light must pass through the glass plate twice is also objectionable. Polished 40 metal reflectors are very efficient when new, but they tarnish very rapidly and soon lose their efficiency.

The present invention contemplates the construction of a reflector having the body 45 portion made of earthenware or other material that will take a glaze, the body being coated with a thin film of a reflecting substance which is fired into the glaze of the earthenware in the manner employed for the 50 decoration of china and similar articles. The body of the reflector may be of stoneware, porcelain, or any other form of earthenware or other material to which a glaze may be applied.

55 In Fig. 1 the body of the reflector is represented by the numeral 7, and a film of re-

flecting substance is indicated as covering the concave side of the reflector at 8. It is not intended to represent the relative proportions of the coating 8 to the body portion 7, 60 but the section is only diagrammatic to show the position of the coating upon the body portion of the reflector. As a matter of fact the coating 8 is much thinner than is indicated by the figure, and is in fact only a very 65 thin film upon the surface of the body portion.

To produce the reflecting surface upon the earthenware body the material commonly employed for producing silver decorations 70 upon china and known by the trade name of "silver bright" may be used. This material as a matter of fact is usually composed chiefly of platinum instead of silver as the name would indicate, and is prepared by 75 rubbing up finely divided platinum in a viscous material, such as spirits of turpentine mixed with fat oil, or thick gum water. Due to the finely divided state of the platinum the material has a dark brown color and does 80 not show a metallic luster until after it is applied. While a material prepared in this way is the best one now known to me for the purpose, it will be understood that other coating materials may be used, such as gold 85 and silver, prepared in a similar manner, or other materials which will stand firing, and which when applied will produce a reflecting surface.

In preparing a reflector the earthenware 90 is shaped into the desired form and burned and glazed in the usual manner. After the earthenware body has thus been prepared, the reflecting surface, which is commonly a concave surface, is coated with a thin film 95 of the reflecting material, such as that previously described, and the reflector thus prepared is placed in a kiln and burned in the manner well known in china decorating. The heat of the kiln causes the metal coating 100 to be absorbed in the glaze on the earthenware body so that after the firing is complete, the coated surface has a brilliant reflecting surface, very closely resembling a highly polished surface of a solid metallic 105 reflector. In some cases it may be desired to apply a second coating of glaze on top of the metallic coating, but this is usually not necessary as the metal which has been burned into the original glaze of the earthenware 110 body is protected by the glaze and is not affected in any way by heat from the

source of light, or by rubbing of the surface coated. The reflector when once completed is practically indestructible so long as the earthenware body is not broken, for the metallic coating does not tarnish, being thoroughly covered by the glaze of the earthenware, and will not peel under the influence of heat and light.

5 The cost of a reflector constructed according to the present invention is very slight compared with other forms of reflectors, for the reason that the earthenware is easily formed into various desirable shapes, and the coating of metal is so thin that the cost 10 of the metal employed is almost negligible.

10 In the form of invention shown in the drawing, light housing 7 is composed of earthenware or similar material and is provided with a reflecting surface 8 burned upon the concave face of the interior of the housing to form a reflector for the light emanating from a lamp shown at 9. The reflecting surface of the interior of the housing may be made in any desired shape, the 15 form shown in the drawings being parabolic, as this is the form commonly used in flood lights. The lamp 9 is secured to the interior of the housing 7 at the bottom thereof, there being an opening 10 to admit the wires 11 which carry current to the light. The lamp socket 12 is held in place by screws 13 which extend through slots 14 formed in the base of the housing 7 and elongated to permit of adjustment of the 20 lamp 9 toward and away from the reflecting surface 8. The adjustment of the lamp is for the purpose of properly relating the source of light to the focus of the reflecting surface. The housing may be secured upon any suitable support 15 by screws 16 passed 25 downwardly through the base of the housing into the support. The housing is preferably provided with a glass front 17 held in place by a frame 18 and screws 19. 30 Ventilator openings 20 are formed in the base of the housing, and similar openings 21 are provided in the part of the housing above the lamp 9, but do not extend directly through the housing as do the openings 20. The openings 21 are provided 35 with ducts 22 which extend laterally from the top of the housing within the material of which the housing is composed and open at points at 23 beneath an overhanging flange or weather shed 24. This arrangement 40 will permit free circulation of air through the interior of the housing, but will protect the light 9 against the entrance of rain or moisture from other sources.

45 60 With this construction it will be seen that the housing for the light and the reflector are formed in one piece at small expense

and that the housing is made of material which is not affected by corroding agencies, so that barring breakage, its life is practically unlimited.

I claim:—

1. A projecting lamp comprising a housing made of earthenware and shaped to provide an inner reflecting surface, a metallic 70 coating secured to said surface and held thereon by glaze material, said earthenware housing having ventilating ducts formed therein and connecting the interior of said housing with the outer atmosphere, the 75 outer openings of said ducts being disposed below the interior openings of said ducts when said housing is in upright position to prevent entrance of moisture through said ducts into said housing. 80

2. A projecting lamp comprising an earthenware housing shaped to provide a concave inner reflecting surface, said surface being unbroken at the central rear portion thereof and ventilating ducts formed 85 in the wall of said housing and having the inner openings therefor offset relative to the external openings.

3. A projecting lamp comprising an earthenware housing having the interior 90 thereof shaped to form a parabolic reflector, a mounting for a lamp on the wall of said housing at a position removed from the parabolic axis of said reflecting surface to permit said reflecting surface to remain un- 95 broken at the rear central portion thereof; a metallic coating on said surface and ventilating ducts formed in the walls of said housing and having inner and outer openings thereto offset relatively to one another 100 to prevent entrance of moisture into said housing through said ducts.

4. A projecting lamp comprising an earthenware housing shaped to provide a substantially parabolic inner reflecting surface, a mounting for a light secured to the wall of said housing at a point removed from the parabolic axis of said reflecting surface to leave the rear central portion of 105 said reflector unobstructed; a metallic reflecting coating on said parabolic surface and held in place thereon by glaze material and having a coating of glaze material covering said metallic coating and ventilating ducts formed in the walls of said hous- 110 ing and having inner and outer openings therefor offset relatively one to another, the upper openings of said ducts being pro- 115 tected by an overhanging flange.

In testimony whereof I have signed my 120 name to this specification on this 20th day of February A. D. 1919.

PATRICK A. NIRDLINGER.
